UNITED STATES PATENT OFFICE.

LANGDON SHOOK THOMPSON, OF LAFAYETTE, INDIANA.

DESIGN FOR A DRAWING-SQUARE.

SPECIFICATION forming part of Design No. 14,973, dated April 22, 1884.

Application filed March 4, 1884. Term of patent 7 years.

To all whom it may concern:

Be it known that I, L. S. THOMPSON, of Lafayette, in the county of Tippecanoe and State of Indiana, have invented and produced a new and original Design for a Drawing-Square, of which the following is a specification, reference being had to the accompanying drawing, forming part thereof.

The drawing is a plan view of my newly-designed square.

The leading feature of my design consists of an angular projection on the head or cross-piece of a T-square.

A indicates the head, and B the blade, of a T-square. The head is provided with an an-

gular projection, C, which is located at its transverse center. The angle formed by the edges of this projection with each other may be of any desired number of degrees, and the projection, as well as other parts of the square, may be provided with graduated scales.

What I claim is --

The design for a T-square, the same consisting of the square having the angular projection C upon the head A, as shown and described.

LANGDON SHOOK THOMPSON.
